UNITED STATES PATENT OFFICE.

SYDNEY OSTERWEIL, OF NEWARK, NEW JERSEY, ASSIGNOR TO L. GOLDSMITH & SON, OF NEWARK, NEW JERSEY, A FIRM COMPOSED OF DAVID OSTERWEIL, NATHAN GOLDSMITH, SYDNEY OSTERWEIL, AND LEON OSTERWEIL.

DRAWER-LOCKING DEVICE.

1,343,742.

Specification of Letters Patent. Patented June 15, 1920.

Application filed May 7, 1917. Serial No. 166,856.

To all whom it may concern:

Be it known that I, SYDNEY OSTERWEIL, a citizen of the United States of America, and a resident of Newark, in the county of 5 Essex and State of New Jersey, have invented new and useful Improvements in Drawer-Locking Devices, of which the following is a specification.

This invention relates more particularly 10 to that kind of drawer locking devices which are employed to simultaneously lock and unlock a series of drawers by closing or opening a single movable part, and especially to such devices which are locked by 15 closing and locking one of the drawers.

The objects of the invention are to provide such a drawer locking device particularly adapted for use upon drawers in a 20 wardrobe trunk; to automatically keep the drawers locked until the trunk is stood upon its right end; to avoid unnecessarily decreasing the depth of the drawers from front to back; to obtain a rigid and durable construction adapted to withstand the hard 25 usage to which a trunk is subjected, and to obtain other advantages and results as may be brought out in the following description.

Referring to the accompanying drawings in which like numerals of reference indicate 30 the same parts throughout the several views:

Figure 1 shows an open trunk with a drawer section in front elevation and two of the lower drawers removed;

Fig. 2 is a vertical central section of the 35 drawer section showing the top drawer partially slid out;

Fig. 3 is a perspective view of a portion of the back wall of the drawer section, showing the upper end of a certain locking member thereon;

Fig. 4 is a perspective view of the upper 40 drawer with the lifting cam mounted upon the back thereof, and

Fig. 5 is a perspective view of one of the 45 locking hooks.

In the specific embodiment of the invention illustrated in said drawings the reference numeral 1 indicates a drawer section and reference numeral 2 indicates the 50 cover section therefor of a wardrobe trunk. In the drawer section, are a plurality of drawers 3 slidably mounted on suitable ledges 4, as is customary, to permit the drawers to be drawn out as desired.

Upon the inside of the back wall of the 55 drawer section I slidably mount preferably a rod 5 longitudinally of the section behind all the drawers. As shown, this rod is substantially at the middle of the back wall and carried in any suitable bearings 6 secured to the wall, it being preferable to position the rod very close to the wall so that only a small clearance space is left therebetween. The upper end of the rod 60 behind the top drawer preferably bends outward as at 7, toward the front of the drawer section and then laterally substantially parallel to both the top and back walls of the section, as at 8, and then inwardly again toward the back wall as at 9, 65 thus forming a transverse U-head at the top of the rod for purposes next described. The end of the rod projecting inwardly toward the back of the trunk may be turned 70 downwardly again if desired, as at 10, parallel to the body portion of the rod and may extend as far down as found desirable, both for preventing the rod from rotating and for affording additional support and 75 guidance to the rod.

Upon the back of the upper drawer is secured a lifting bracket or cam 11. This lifting bracket is preferably at substantially the middle of the back of the drawer or otherwise positioned to coact with the 80 above described head on the rod to engage said head and lift the rod when the drawer is slid all the way in and hold it lifted until the drawer is again slid outward.

Behind all of the other drawers, that is, 85 all the drawers except the top one, transverse cross-rods or pins 12 project from the vertically slidable rod 5, said pins being fast with respect to the rod and obviously all lifted at the same time by lifting the rod 5. 90 Upon the backs of all of the drawers, except the top one, are secured hooks 13 which have a lower lip-portion 14 spaced away from the back of the drawer and extending downwardly in such a manner that upon lifting the rod 5, when the drawers are slid all the way in, the transverse pins 12 will enter between the said lip-portions 14 of the hooks and the backs of the drawers and thereby prevent the drawers from being 95 withdrawn until said pins are lowered again. Obviously, all of the drawers below the top one may therefore be locked closed by clos- 100

- ing the top drawer. Preferably, the said hooks 13 have their lower free or lip-portion 14 spaced only far enough away from the backs of the drawers to receive the pins 12 without any material lost motion, so the drawers will not have to be decreased materially in depth from front to back, the locking means described taking up very little room. While I have shown only one hook 10 upon each drawer, it will be understood more may be used if desired, for instance, one near each end of the drawer, with the pins 12 extending both ways from the rod and long enough to engage said hooks.
- 15 As shown, suitable stops 15 are provided near the opposite ends of the drawers at their backs, preferably upon the trunk section, to limit the position to which said drawers may be slid inwardly of the trunk 20 section. The upper drawer which obviously, because of its cam shaped bracket and the U-head on the vertically slidable rod has to be of slightly less depth from front to back than the other drawers, is limited in its inward movement by a stop 25 16 in the trunk so placed that said upper drawer will close flush or even with the other drawers. Furthermore, a suitable lock 17 is provided for the upper drawer 30 whereby it may be secured against opening, and obviously if the other drawers have been locked by raising the rod as this upper drawer is closed, they also will be locked against withdrawal until the upper drawer 35 is unlocked and slid outward.
- The construction as thus described, provides a locking means at the back of the drawers which will hold all of said drawers closed until said means releases by gravity.
- 40 When the trunk is delivered and opened, if it is stood on its wrong end, the sliding rod 5 will hold all the drawers, except the one secured by lock and key, from being opened,

so the contents of the drawers cannot be spilled out through inadvertence, carelessness or ignorance. However, when the trunk is stood upon its right end and the upper drawer opened enough to permit the rod 5 to drop, the pins will release from the hooks and thereby release or unlock the other drawers.

Obviously various modifications and changes may be made in the manufacture of my improved drawer locking device without departing from the spirit and scope of the invention, and I do not wish to be understood as limiting myself except as required by the following claims when construed in the light of the prior art.

Having thus described the invention, what I claim is,

The combination with a compartment and a series of drawers therein, of a locking member comprising a slidable metal rod at the inner ends of said drawers, a portion of said rod being forwardly and then laterally offset adjacent and substantially parallel to the inner end of one of the drawers, said portion of the rod then extending rearwardly and substantially parallel to the main portion thereof, means for slidably supporting said rod within the compartment, said supporting means engaging the rod at opposite sides of said offset portion to prevent rotation of said rod, means on the said one of the drawers to engage said offset portion of the rod to operate the rod, and co-acting means on the other drawers and said rod for locking said other drawers.

In testimony whereof I have signed this specification in the presence of two subscribing witnesses.

SYDNEY OSTERWEIL.
